UNITED STATES PATENT OFFICE.

WILLIAM D. HALL, OF CHICAGO, ILLINOIS.

BED-RAIL.

SPECIFICATION forming part of Letters Patent No. 743,073, dated November 3, 1903.

Application filed May 7, 1903. Serial No. 155,981. (No model.)

To all whom it may concern:

Be it known that I, WILLIAM D. HALL, of Chicago, Illinois, have invented certain new and useful Improvements in Bed-Rails, of which the following is a specification.

This invention relates to improvements in bed-rails, and more particularly to a short form of rail adapted to be used in connecting the head and foot members of a bedstead 10 close together for the purpose of exhibition where economy of floor-space and ease in shifting them about upon the floor are desired.

Among the salient objects of the invention are to provide a device of this kind which is 15 simple and economical of construction, to provide a device which can readily be applied to the end members of any of the ordinary forms of bedsteads, and to provide a device which when applied to such end members will hold 20 them in a rigid upright position and yet possessing sufficient flexibility to respond to the weight of said members in their tendency to stand with all four feet upon the floor at the same time, thus avoiding the tottering and un- 25 steady position of repose common when the ordinary connecting-rails for exhibiting purposes are used.

The invention consists in the matters hereinafter described, and more particularly pointed out in the appended claims, and will be readily understood from the following description, reference being had to the accompanying drawings, in which—

Figure 1 is an edge view of the head and 35 foot members of a bedstead, showing a modified form of my invention in operation. Fig. 2 is a side plan view of the preferred form of my invention. Fig. 3 is a top plan view of Fig. 2. Fig. 4 is a top view taken on line 4-4, 40 Fig. 1, with certain parts broken away.

Similar numerals refer to similar parts throughout the several figures.

1 and 2 represent the head and foot members, respectively, of a bedstead used to show 45 the application of my invention. 3 and 4 are supporting-blocks secured to the side posts of said head and foot members in the usual manner and having formed therein the sockets 3' and 4'. (Shown in Fig. 4.)

5 represents my invention as a whole, and, as will be seen by reference to Figs. 2 and 3, it consists of a short and comparatively thin

strip of resilient metal (designated as 6) placed edgewise between two metal attaching-blocks 7, formed of cast-iron or the like. 55 These are preferably cast to the ends of said strip in the form shown, with the conical-shaped shoulders 8 adapted to fit into similarly-shaped sockets 3' 4' in the supporting-blocks 3 and 4, thus insuring a rigid joint 60 therebetween and one which can readily be taken apart when desired.

By making the connecting-strip 6 of resilient metal and placing it edgewise between the attaching-blocks in the manner shown it affords a connection which is sufficiently rigid to prevent a tilting in either direction of the end members and at the same time permits of sufficient torsional movement under the weight of said members to adapt them to any 70 unevenness in the floor-surface and to allow all four feet to rest upon the floor at the same time.

I am aware that it is common to make short connecting-bars for exhibition purposes of 75 wood and also of angle-iron, such as the full-length bars are made of; but these have their objections in that the wood bars are very soon so worn at the points of contact with the iron through being shifted about so much as to 80 cause a tilting and unsecure connection between the members and often drop out of the sockets and allow the members to fall upon the floor, while with the short angle-iron members they are so stiff that the tendency is, unless fitted to the particular members with 85 which they are to be used, to cause a tottering and unsteady position of said members and will not permit them to adapt themselves by reason of their own weight to the floor- 90 surface upon which they are placed. These objections are overcome in my invention.

In Fig. 1 I have shown a modified form of my invention in which instead of a single strip connecting the attaching-blocks two rod-like members 6' are used with the same desired effect. 95

It will be evident that variations in the form of the different parts may be made without departing from the spirit of the invention, 100 and I do not, therefore, restrict myself to the particular construction shown.

I claim—

1. A show-room bed-rail, comprising end

blocks adapted for rigid engagement with the
sockets of head and foot members of a bed-
stead, and means connecting said blocks com-
prising one or more short relatively thin re-
silient strips arranged in a vertical plane and
rigidly united with said blocks, whereby the
blocks and connected bedstead members are
susceptible of torsional movement, but held
rigid against tilting toward or from each
other.

2. A show-room bed-rail, comprising end

blocks adapted for rigid engagement with the
sockets of head and foot members of a bed-
stead, and means connecting said blocks com-
prising a short relatively thin resilient metal ¹⁵
strap arranged with its plane vertical, and
having its end rigidly seated in the respective
blocks.

WILLIAM D. HALL.
